UNITED STATES PATENT OFFICE.

HANS SCHWENNEKE, OF CHICAGO, ILLINOIS, ASSIGNOR TO GLOBE PAPER BOX COMPANY, OF CHICAGO, ILLINOIS.

PASTEBORD BOX.

Application filed April 26, 1921. Serial No. 464,580.

To all whom it may concern:

Be it known that I, HANS SCHWENNEKE, a citizen of the United States, and a resident of Chicago, in the county of Cook and State 5 of Illinois, have invented certain new and useful Improvements in Pasteboard Boxes, of which the following is a specification.

My invention relates to pasteboard boxes, such as used for containing and displaying 10 merchandise, for example, and is particularly directed to an inner cover of the box, an object of which is to protect the contents from dust and air, supplemental to the usual flanged cover for enclosing the top of the 15 box.

A prime object of the inner cover is to afford a salient space for advertising the contents of the box. For example, the usual outer cover of the box would be disposed of and 20 the inner cover opened to display the contents of the box and the advertising matter on the inner side of the inner cover. In order to protect the contents of the box at 25 night from air and dust, for example, the inner cover may be swung into the covering position.

A display box incorporating the present invention is shown in Fig. 1 of the accompanying drawing.

30 Fig. 2 shows a vertical section of the box with one side thereof and also the corresponding flange of the cover removed.

Fig. 3 shows a plan elevation of the box with the cover removed and the inner-cover 35 raised and it also indicates a portion of the inner-cover where adhesively secured to the sides of the box proper.

Fig. 4 shows the inner cover member in 40 somewhat detailed form with particular reference to its relation to the box proper.

The pasteboard box 1 may be of the usual form used for containing merchandise, into which is adhesively secured the inner-cover 45 which has a top 2 designed to be swung upwardly. Flaps 3 are designed to be folded inwardly and lie parallel to the top of the inner-cover 2 when the inner cover is placed in the position covering the top of the box. Crease 4 defining one edge of the portion 5

50 and crease 6 defining the lower edge of the portion 5 enable the portion 5 to be swung inwardly and at the same time permit the flap 3 to be folded into a plane parallel with the inner-cover 2. That is to say, the portion 55 5 can be folded inwardly along the crease 6,

and the top of the inner-cover 2 can be swung to cover the top of the box and the flap 3 will swing inwardly parallel to the top of the inner cover so that the flap 3, and the portion 5, which latter may be 60 termed a segment, will fold so that the outside faces thereof will become facing and the inside face of the flap 3 will face the inside face of the inner-cover 2. Segments 7 which are defined along the line 6 and 65 along the line defining the segment 8 from the segment 7 is adhesively attached to the inner-side of the box 1. The segment 8 is also adhesively attached to the inner-side of the box, and likewise the segment 9 is 70 adhesively attached to an inner end of the box.

The V shaped open portion between segments 8 and 9 is formed when the segment 7 is raised in order to bow flap 3 and the 75 portion 5 inwardly while the inner cover 2 is perpendicular with respect to the bottom of the box. This latter arrangement thus permits the cover 2 to be gyrated backward so that it tilts backward before the flap 3 80 and the portion 5 straighten into the same plane to serve as a check against the further backward gyration of the cover 2. It will thus appear that the cover has a swing of over 90 degrees from its closing position before being checked by its folding edges. I 85 am aware that tops of pasteboard boxes with folding members have heretofore been used, but so far as I am aware I am the first to construct such a cover with retaining 90 flaps as a portion thereof which will permit the cover to gyrate past a line perpendicular with its fixed portion.

It will thus be clear that the inner-cover 95 can be inwardly swung around the creased line 11 so that the portion 2 will swing within the box and preferably lie parallel with the bottom of the box, as it would should the box be filled with merchandise, for example, the flap 3 and the segment 5 100 folding inwardly and lying parallel to the top portion 2, and not occupying appreciable space within the box.

It will be thus clear that the outer cover 105 of the box 10 can be removed and the inner cover swung upwardly where it will be retained and limited in its gyration by reason of the segment 5 and the flap 3 so that the 110 contents can be readily removed or displayed. It will be clear that the crease 4

defining the flap or segment portions 4 and 5 will form a supplemental hinge for the cover, and it will also serve to restrain the cover portion from lateral movement as well as acting to stiffen the support of the cover.

The drawings and descriptions thereof contemplate but one form of inner-cover employing the present invention, but it is to be understood that I do not wish to be limited to the exact structure shown, but desire to include and cover all modifications thereof as may readily be made in adapting it to various forms of pasteboard boxes and the like, in view of the subjoined claims.

I claim:

1. In a pasteboard box or the like, a cover singly hinged from a side of the box having a folding pasteboard portion thereof which forms a supplemental hinge for the cover and which will unfold to form a means to limit the gyration of the cover, the limit of gyration being beyond the line of the side of the box to which the cover is hinged, so the angle between the inside face of the cover and the inside face of the hinged side of the box will be more than one hundred and eighty degrees.
2. In a pasteboard box or the like, a cover member approximating the dimensions of the open portion of the box to be closed, but smaller than the said opening, the said cover member being singly hinged from a side of the box and having a folding portion thereof which will unfold to form means to limit the gyration of the cover, the limit of gyration being beyond the line of the side of the box to which the cover is hinged, so the angle between the inside face of the cover and the inside face of the hinged side of the box will be more than one hundred and eighty degrees.
3. In a pasteboard box or the like, a secondary cover member approximating the dimensions of the open portion of the box to be closed, but smaller than the said opening, the said cover member being singly hinged from a side of the box and having a folding portion thereof which will unfold to form means to limit the gyration of the cover, the limit of gyration being beyond the line of the side of the box to which the cover is hinged, so the angle between the inside face of the cover and the inside face of the hinged side of the box will be more than one hundred and eighty degrees.
4. In a pasteboard box or the like an auxiliary cover member approximating the dimensions of the open portion of the box to be closed, but smaller than the said opening, the said cover member being singly hinged from a side of the box and having a folding portion thereof which will unfold to form means to limit the gyration of the cover, the limit of gyration being beyond the line of

the side of the box to which the cover is hinged, so the angle between the inside face of the cover and the inside face of the hinged side of the box will be more than 180 degrees, and a primary cover for enclosing the auxiliary cover and the opening of the box.

5. In a pasteboard box or the like, a sheet cover portion singly hinged from a side of the box having folding sheet flaps as an integral portion of the cover which said flaps form supplemental hinges for the cover and which will unfold to limit the gyration of the cover, the limit of gyration being beyond the line of the side of the box to which the said cover portion is hinged, so the angle between the inside face of the said cover portion and the inside face of the hinged side of the box will be more than one hundred and eighty degrees.

6. In a pasteboard box or the like, a cover portion and folding flaps therefor formed of a single sheet of material the said flaps forming supplemental hinges for the cover portion, the said cover portion singly hinged from a side of the box, creases defining the flaps for folding the faces of same generally parallel with the inside face of the cover portion, and means of attaching the flap portion to the box whereby when the cover portion is gyrated from its covering position the flaps will unfold an agency to limit the gyration of the cover portion, the said gyration being over ninety degrees from its covering position.

7. In a pasteboard box or the like, a cover portion having folding flaps the said flaps forming supplemental hinges for the cover portion, the said cover portion singly hinged by a crease from a first side of the box, creases defining the flaps of the cover portion and a second side of the box so the said flaps can be folded generally parallel with the inside face of the cover portion whereby the flaps when unfolded form an agency to limit the gyration of the cover, the said gyration being over ninety degrees from its covering position.

8. In a pasteboard box or the like, a cover portion having folding flaps the said flaps forming supplemental hinges for the cover portion, the said cover portion singly hinged by a crease from a side of the box, creases defining the flaps of the cover portion and a side adjacent to the said first side, whereby the said flaps can be folded generally parallel with the inside face of the cover portion so when the cover portion is gyrated from its covering position the flaps will unfold and form a limiting agency to restrain the cover portion from gyrating beyond a predetermined angular distance, the said distance being over ninety degrees.

9. In a pasteboard box or the like, a cover portion having folding flaps, the said flaps

forming supplemental hinges for the cover portion, the said cover singly hinged by a crease from a side of the box, creases defining flaps of the cover portion and a side adjacent to the said first side, whereby the said flaps can be folded generally parallel with the inside face of the cover portion so when the cover portion is gyrated from its covering position the flaps will unfold and form a limiting agency to restrain the cover portion from gyrating beyond a predetermined angular distance, the said distance being over one hundred and eighty degrees counted from the inside face of the hinged side. 10

5

In witness whereof, I hereunto subscribe 15 my name this 23 day of April, A. D., 1921.

HANS SCHWENNEKE.
